METHOD AND MEANS FOR APPLYING SLIDE
FASTENERS TO ARTICLESBurleigh B. Peterson, Duluth, Minn., assignor to
Talon, Inc., a corporation of Pennsylvania

Application February 8, 1933, Serial No. 655,806

10 Claims. (Cl. 112—151)

This invention relates to metal slide fasteners and has special reference to the application of any type of such to any form of garment; the principal objects of which are the saving of time and thread, and the assurance of perfect application, in one operation, of the fasteners to the finished product.

It is well known that the application of metal slide fasteners by single needle operation is neither practical nor economical, and failure of fasteners to operate is usually traced to faulty application, the reason for which is due to the fact that the slides have to be applied, each side separately, with the chance of irregularity after the operation is done. The hereinafter described invention eliminates all of the above defects by applying the fasteners to the garments in closed position, and thus both sides of the fasteners have to be uniform.

Through the use of this device the saving in thread alone amounts to approximately 50%, and the cost in labor is cut down at least 80%, and the device can be attached to any compound feed, two needle machine, and the gauge of needles, and device, would have to be supplied according to size, and type of fastener to be used.

Other objects and advantages of the invention will appear in the following description thereof.

Referring now to the accompanying drawing, forming part of this application, and wherein like reference characters indicate like parts:

Figure 1 is an enlarged plan view of the standard presser foot of a two-needle sewing machine, illustrating one embodiment of the invention as applied thereto.

Figure 2 is a section on the line 2—2, Figure 1 showing the needle bar in elevation.

Figure 3 is a front elevation of the presser foot proper, illustrated as slightly modified.

Figure 4 is a reduced elevation of a sewing machine head with the device attached.

1 represents the presser foot bar of a two needle machine, 2 the needle bar, and 3 and 4 the presser foot; 3 being the arcuately shaped support for the presser foot proper which is pivotally carried thereupon as at 5, the vertically extending portion 6 of the support 3 being insertable within the slot in the lower end of the presser foot bar and held there as by a suitable screw 7. For accommodation of the united rows of the fastener element which are carried upon the fabric strips, the presser foot proper 4 is slightly channeled as at 8, (see Fig. 3).

Just back of the uppermost angle of the support 3 is fixed thereto the horizontally disposed

cylinder 9, it being in length approximately twice the width of the presser foot proper, and rotatably carries therein the supporting shaft 10 of the pivotal portion 19 of the guide. The cylinder, or hollow shaft 9, also rigidly supports the downwardly disposed and arcuately shaped frame like structure 11 (made of resilient material) which also extends forwardly of the presser bar and supports the lower members of the guide for the material passing therethrough. The lower frame structure consists of two identical members, each sufficiently rigid to support itself independently of the other as the wings of same are spaced slightly apart as at 12 and are of flat sheet metal, extending backwardly and the flat horizontal portion of each being illustrated at 13, though provided with an upstanding side flange 14 which is turned inwardly for a short distance as at 15 just inwardly of the uppermost wings 16, then turned inwardly still further as at 17 the remainder of their distance to substantially the converging point of same with the sides of the presser foot 4, thus forming a side channel like member for guidance of the material to which the fastener is being attached as it passes through the machine. The approximate meeting point of the presser foot and horizontal flanges of the channel is in substantial alignment with the pivotal point 5 of the presser foot proper, or these channels may extend to the forward end of the presser foot.

In the embodiment here illustrated I have shown the wings 13 as simply soldered or otherwise fixed upon the inwardly extending and arcuately shaped ends 18 of the members 11, though it is obvious these two members may be of one integral piece if preferred, or otherwise assembled.

The uppermost pivotal frame structure, illustrated at 19, is carried upon the shaft 10, previously described, and is thus pivotally mounted, having its free end susceptible of vertical swinging adjustment upon said shaft. Just forwardly of this shaft is a second transverse shaft 20, fixed to the side members of the frame 19 which by the way is somewhat wider than the lower frame, composed of the members 11. This shaft 20 forms a reinforcement to the frame 19 and is designed to engage beneath the spring hook 21 rigidly fixed to the hollow shaft 9 for the purpose of holding the frame 19 up out of the way when initially applying the work to the machine. Upon the tubular shaft 9 at one end thereof is mounted the helical spring 22, one end of which is hooked over the shaft 20 as at 23 for the purpose of bias-

ing the frame 19 to its closed and cooperative position with the free winged termini of the lowermost frame.

This upper pivotal frame structure is so shaped as to provide a suitable handle like protrusion 24 for manipulation thereof, and inwardly of the extreme outer end of which is carried upon the under side of said frame the transverse sheet metal wing element 16, the sides of which are arcuate in shape as viewed from the front thereof and carry centrally a thin depending guiding member 32 which is here shown as being formed by a tight fold in the thin metal, and extends intermediate of and below the wings 13 when the device is closed for operation. In this manner the two sets of wings form an efficient guide for the folds or hem on the edges of the garment to which the fastener is being applied. The hems of the two parts of the garment are first formed by hand and tucked in to proper position on top of the lowermost wings and under the upwardly turned front end of the presser foot before the upper wings are brought down onto same.

When the hems of the garment are thus initially positioned and the upper wings brought down upon same where they are properly tensioned by the spring 22 as before described, then the assembled fastener strip is placed with its lowermost end underneath the upwardly turned free end of the presser foot; it being understood that the vertically extending sides 14 which are flanged inwardly as previously described are the proper distance apart to receive the thus flatly assembled fastener, which brings the opposed carrying strips of the fastener centrally aligned under each needle, so that as sewing progresses the needles will be positively and properly aligned centrally of each fastener strip and the fold of the garment as they together pass beneath the presser foot, completing the process in a single and very efficient operation.

It will be noted that the lateral resiliency of the wings 13 is essential for accommodation of the two thicknesses of cloth obliged to pass therebetween and which may vary somewhat in thickness; in fact the wings may be slightly changed in form to accommodate special circumstances without departing from the spirit of the invention.

I have shown the uppermost wing 16 as having a central depending guiding fin 32 for separation of the two pleats or folds as they enter the machine.

In operation, the two parts of the garment or article to which the fastener is to be applied, 55 are placed right side of material down on the cloth plate of the sewing machine under the folders 13 with their edges extending upwardly between said folders in the space indicated at 12. A fold is then initially started to form a hem 60 in each side the approximate width of the fastener tapes to be applied, and which is gauged by the guide formed by the upturned edges of the folders 13, indicated at 14. The material is then started by hand back under the presser 65 foot and there held in place by the tension thereof. The upper wing shaped folder operated by the protrusion 24 is then brought down with its centrally depending fin shaped portion 32 dividing said two edges which automatically turns 70 them outwardly and downwardly, thus forming the hem in each.

The closed separable fastener strip is then placed with its lowermost end underneath the upwardly turned free end of the presser foot and 75 over the aforesaid hems, with its central metal

portion engaged in the channel 8 of the presser foot, and the upper end of the fastener is hooked up on tension line 30.

The sewing operation is then started, the operator simply guiding the two edges of the material into the folders where the fastener strip and the two folded edges are centrally aligned between the two needles, simultaneously stitching both parts and the fastener into one separable unit, and completing the process in a single 10 very efficient operation.

It will be readily understood by those versed in the art that the channels formed by the wings and their cooperative side members would require a considerable change in shape for special 15 classes of work to which the slide fastener is being attached, and furthermore the shape of the wing supporting frames might be materially changed for such special accomplishments without departing from the spirit of the invention. 20

For convenience in the operation of the device and particularly of the feeding of the fastener strip 26 to the device I have illustrated an upright support 27 fastened to one side of the machine head, bent over and carrying in its upper 25 bent portion the sheaves 28 and 29 so that a tension line 30 may be passed over these sheaves and attached at one end to the strip, while a weight to counterbalance same is attached at the other end as at 31. This provides a practical 30 means for holding the loose end of the strip out of the way and automatically feeding same to the device.

Having thus described my invention, what I claim and desire to secure by Letters Patent, is:

1. A slide fastener applicator comprising in combination a pair of laterally yieldable folder wings for forming a hem in each adjacent portion of a garment to which a fastener may be applied, and a channel like guide in alignment with the discharge end of said folder wings for passage 40 of the folded portions of the garment and the fastener therethrough while being united.

2. The combination with the presser foot of a two-needle sewing machine, of a hem forming guide supported in front of said presser foot, and channel guides extending rearwardly from said hem forming guides and adjacent the sides of said presser foot, whereby material fed into said hem forming guide is directed by said channel guides under the presser foot and through the 50 sewing machine.

3. The process of simultaneously attaching both teeth-strip members of a separable slide fastener to the contiguous edges of the material to be held by the fastener which consists of juxtaposing the edges of the material to be held by the fastener, interengaging the complementary toothed portions of the fastener, throughout the entire length of the teeth-strips, superposing the interengaged fastener teeth-strips upon the juxtaposed edges of the material to be held and so positioning them that the central line of contact of the interengaged teeth of the fastener is approximately in registration with the juxtaposed edges of the material to be held, and simultaneously uniting each strip of the interengaged teeth-strips of the fastener beyond the teeth parts of the strip to its respective edge of the juxtaposed edges of the material to be held.

4. The process of simultaneously attaching 70 two cooperating strip members of a separable fastener to the contiguous edges of the material to be held by the fastener which consists of juxtaposing the edges of the material to be held by the fastener, interengaging the complementary 75

portions of the fastener, superposing the interengaged fastener strips upon the juxtaposed edges of the material to be held and so positioning them that the central line of contact of the 5 interengaged elements of the fastener is approximately in registration with the juxtaposed edges of the material to be held, and simultaneously uniting each strip of the interengaged strips of the fastener beyond the fastener parts of the 10 strip to its respective edge of the juxtaposed edges of the material to be held.

5. The method of applying simultaneously the closed members of a separable fastener to separate contiguous edges of the material to be held 15 by the fastener which consists in placing the edges of one end of the material to be held by the fastener in juxtaposition, superposing one end of the closed fastener members upon the end of the juxtaposed edges of the material to be held, and so positioning them that the central line of contact of the closed members of the fastener is approximately 20 in registration with the juxtaposed edges of the material to be held, and simultaneously uniting each member of the closed separable fastener beyond the fastener parts of the 25 member to its respective edge of the juxtaposed edges of the material to be held.

6. The method of applying simultaneously the closed members of a separable fastener to separate contiguous edges of the material to be held 30 by the fastener which consists in placing the edges of one end of the material to be held by the fastener in juxtaposition, superposing one end of the closed fastener members upon the end 35 of the juxtaposed edges of the material to be held and so positioning them that the central line of contact of the closed members of the fastener is approximately in registration with the juxtaposed edges of the material to be held, and simultaneously forming a hem in each juxtaposed edge of the material to be held, and uniting each fastener member to its respective hem.

7. The process of simultaneously hemming the contiguous edges of material to be held by a separable fastener and attaching to the hems two closed strip members carrying complementary fastener elements which consists of forming a hem fold in each of the edges of the material to be held by the fastener, juxtaposing such hem-folds of the material to be held, interengaging 45 the complementary elements of the fastener, superposing the interengaged fastener upon the 50

juxtaposed folded edges of the material to be held, positioning the central line of contact of the interengaged elements of the fastener substantially in registration with the juxtaposed contacting edges of the hem-folds of the material to be held by the fastener, and simultaneously completing the hems and uniting each strip of the interengaged strips of the fastener beyond the fastener elements of the strip to its respective hemmed edge of the material to be held by a single series of stitches thru each hem and its respective strip of the fastener.

8. In a device for forming hems in the juxtaposed edges of fabrics and for simultaneously sewing one part of a closed slide fastener to each hem, the combination of a guide and hem-former for attachment to the presser foot of a two-needle sewing machine having a lower part composed of two wings held in contact when empty centrally of the guide by fixed resilient arms, a 15 hinged upper part held resiliently in contact with the upper surface of the fabric, flanges on the outer edges of the wings of the lower part of the guide, a downwardly projecting fin centrally of the upper part of the guide, a twin needle presser 20 foot having a groove centrally located in its lower surface to accommodate a closed slide fastener, a spring hook fixed to the presser foot to engage the upper part of the guide and hold it in inoperative position while the hems are initially 25 formed and placed in the device, and means for guiding a closed slide fastener thru the groove in the presser foot and above the hems formed in the fabric.

9. A device for securing slide fasteners to a 30 garment comprising a presser foot for attachment to the presser foot bar of a sewing machine, laterally yieldable means fixed to said foot for guiding the edges of the garment in juxtaposed relation with the fastener thereupon through the 35 device, and means for causing a hem to be formed in each edge of the garment as it passes through the device.

10. A device for securing slide fasteners to the 40 juxtaposed edges of a garment comprising laterally yieldable means for folding said edges to form a hem therein as they pass through the device, and means for guiding a slide fastener in closed position through the device and over said 45 hems while being sewn thereto.
